Specification for Design.

Patented Feb. 9, 1915.

Application filed September 30, 1913. Serial No. 792,696. Term of patent 14 years.

To all whom it may concern:

Be it known that I, NAPOLEON B. DOUGLASS, a citizen of the United States, residing at Berkeley, county of Alameda, State of California, have invented a new, original, and ornamental Design for a Wall-Bed Head and Frame, of which the following is a specification, reference being had to the accompanying drawing, forming part thereof.

The bed head frame is rectangular in outline with straight vertical and horizontal reaches A merging smoothly into rounded

corners B at both top and bottom. Straight bars C radiate from the center of the bottom reach to the center of the upper reach and upper rounded corners.

I claim:

The ornamental design for a wall bed head and frame, as shown.
